DESCRIPTION

FIG. 1 is a perspective view of a reach lift truck from the left front of the truck showing our new design;

FIG. 2 is a perspective view thereof with disclaimed material being removed;

FIG. 3 is a perspective view thereof taken from the right rear;

FIG. 4 is an elevational front view thereof;

FIG. 5 is an elevational rear view thereof;

FIG. 6 is an elevational right side view thereof;

FIG. 7 is an elevational left side view thereof; and,

FIG. 8 is a top view thereof.

The elements shown in broken lines in FIG. 1 are for illustrative purposes only and form no part of the claimed design.
